CLAIM

The ornamental design for a rounded ribbed closure, as shown and described.

DESCRIPTION

FIG. 1 is a perspective view of the rounded ribbed closure of the subject invention.

FIG. 2 is a side view of the rounded ribbed closure of FIG. 1, the opposite side being identical.

FIG. 3 is a top plan view of the rounded ribbed closure of FIG. 1.

FIG. 4 is a bottom plan view of the rounded ribbed closure of FIG. 1.

FIG. 5 is a perspective view of another embodiment of the rounded ribbed closure of the subject invention having a tamper evident band.

FIG. 6 is a side view of the rounded ribbed closure of FIG. 5.

FIG. 7 is a top plan view of the rounded ribbed closure of FIG. 5; and,

FIG. 8 is a bottom plan view of the rounded ribbed closure of FIG. 5.
